US00D913379S

(12) **United States Design Patent** (10) **Patent No.:** **US D913,379 S**
(45) **Date of Patent:** **** Mar. 16, 2021**

(54) **GAMING MACHINE**

- (71) Applicant: **AGS LLC**, Las Vegas, NV (US)
- (72) Inventors: **Rachel Calhoun Lewis**, Atlanta, GA (US); **Karl Frederick Zedell, Jr.**, Alpharetta, GA (US); **Sigmund Lee**, Atlanta, GA (US); **Daniel Kendall Harden**, Palo Alto, CA (US); **Robert William Strickler**, Portland, OR (US); **Ariel David Turgel**, San Francisco, CA (US)
- (73) Assignee: **AGS LLC**, Las Vegas, NV (US)
- (**) Term: **15 Years**
- (21) Appl. No.: **29/695,793**
- (22) Filed: **Jun. 21, 2019**

Related U.S. Application Data

- (60) Continuation of application No. 29/646,448, filed on May 4, 2018, now Pat. No. Des. 854,621, which is a (Continued)
- (51) **LOC (13) Cl.** **21-03**
- (52) **U.S. Cl.** **D21/369**

OTHER PUBLICATIONS

Bluebird Slant Widescreen literature from www.wms.com/technologyandinnovation_cabinets_widcscreen.php dated May 19, 2009, showing a gaming machine cabinet that was sold and/or publicly disclosed at least as early as Dec. 13, 2008.

(Continued)

Primary Examiner — Ryan Harvey

(74) *Attorney, Agent, or Firm* — Weide & Miller, Ltd.

(57) **CLAIM**

The ornamental design for a gaming machine, as shown and described.

DESCRIPTION

FIG. 1 is a front perspective view from above of the claimed design;
FIG. 2 is a front elevation view of the claimed design of FIG. 1;
FIG. 3 is a rear elevation view of the claimed design of FIG. 1;
FIG. 4 is a right side view of the claimed design of FIG. 1;
FIG. 5 is a left side view of the claimed design of FIG. 1;
FIG. 6 is a top plan view of the claimed design of FIG. 1; and,
FIG. 7 is a bottom plan view of the claimed design of FIG. 1.

The broken line showing of portions of the gaming machine depicts environment and forms no part of the claim.

1 Claim, 6 Drawing Sheets

Related U.S. Application Data

division of application No. 29/541,557, filed on Oct. 5, 2015, now Pat. No. Des. 818,048.
